UNITED STATES PATENT OFFICE

JAMES A. POWELL, OF RICHMOND, VIRGINIA, ASSIGNOR TO THE AMERICAN TOBACCO COMPANY, OF NEW YORK, N. Y., A CORPORATION OF NEW JERSEY

TELESCOPICALLY COLLAPSIBLE BOX

Application filed April 18, 1929. Serial No. 356,060.

This invention is an improvement in a telescopedically collapsible box, and more particularly in a box or can designed for containing smoking tobacco for retailing.

5 In the usual construction of box of this character, the box is of considerable depth, and the tobacco is usually in a state of some compression. In order to discharge the contents, it is usual to dislodge and loosen a portion thereof with a finger. When the 10 contents are approximately half exhausted, it is very difficult to reach the remaining part of the tobacco to loosen and dislodge it.

One of the primary objects of the present 15 invention is the provision of a box of the character in question, of a nature such that as the contents of the box are removed, the sections may be collapsed to lessen the length of the box, thereby to facilitate access to the 20 remainder of the contents.

Another object is the provision of a box wherein the telescopic sections may be quickly assembled merely by pushing them together, and wherein the sections may be 25 easily separated from each other, without deformation of any part of the sections.

Another object is the provision of a box 30 wherein the connections between the sections is such that they will be held in extended position, whatever the relation of the sections, by friction, and will be releasably locked in fully extended position.

Another object is the provision of a connection 35 such that the natural resiliency of the sections may be utilized in the release and engagement of the lock.

Another object is the provision of a box 40 of this character, so constructed that it differs but slightly in appearance from the usual box, and wherein when the label is in place thereon the difference in appearance is practically negligible.

Another object is to provide a construction 45 such that the cost of the box is not materially increased.

Another object is to provide in such a construction, a smooth and flat joint between the sections of the box, wherein the joint offers a minimum of deformation.

50 With these and other objects in view the

invention consists in the construction and novel combination of parts fully described hereinafter, illustrated in the accompanying drawings, and pointed out in the claims appended hereto, it being understood that 55 various changes in the form, proportion, size and minor details of construction within the scope of the claims, may be resorted to without departing from the spirit of the invention. 60

In the drawings forming a part hereof:—

Fig. 1 is a perspective view of the improved box extended.

Figs. 2 and 4 are sections on the lines 2—2 and 4—4 of Fig. 1. 65

Fig. 3 is a view similar to Fig. 2 with the box collapsed.

In the present embodiment of the invention the improved box which is of sheet metal, or the like, is composed of an upper 70 and lower section, telescopedically connected, to slide one within the other. The box is designed to fit the pocket, and is oblong in horizontal cross section, as shown.

The lower section 1 is provided with a 75 bottom 2 forming a closure at one end of the box, and the upper section 3 is provided with a cover 4 which is hinged to the section as indicated in 5, the cover being the usual flanged cover, fitting the end of the 80 section, which is provided with an annular bead 6, against which the flange of the cover abuts.

The lower end of the upper section fits 85 within the upper end of the lower section, as shown, and mechanism is provided in connection with the sections for releasably holding them fully extended, and for enabling collapse of the sections to any degree, between the positions of Figures 2 and 3. 90 The interlocking mechanism is in the form of depressions in the walls of the sections at their meeting ends. These depressions form bosses 7 and 8 on the outer faces of the sections, and the bosses of the inner section are 95 so arranged with relation to those of the outer section, that the said bosses 7 will fit within the bosses 8, whereby to lock the sections in extended position.

As indicated in Figs. 1 and 4, four sets 100

of interlocking bosses are provided, one set being on each section, and they are so positioned with relation to the meeting ends of the sections, that there will be sufficient lap of the sections when they are interlocked to provide for a stable position. The bosses are arranged on the side walls of the sections, so that the natural resiliency of the sections may be utilized to cause close engagement of the same, and to enable release thereof if this should be necessary, by springing the side walls of the upper section inwardly. The upper section is of a length such that it may be telescoped within the lower section, as shown in Fig. 3, approximately the full depth thereof, this movement being limited by the annular bead 6, before mentioned.

In the use of the improved box, the tobacco is first wrapped in a package, and the wrapped package is inserted into the box. Both of these operations are done by machinery. The wrapped package may be inserted in the box after the sections are assembled, or it may be inserted in the lower section, and the upper section fitted into place. The sections are easily assembled, it only being necessary to push the lower end of the upper section into the upper end of the lower section, until the bosses interlock. The box is then stably held against accidental displacement of the sections. The tobacco is usually removed by loosening the same with the fingers, the tobacco being more or less compact in the package. This operation is continued, and eventually the tobacco is lowered, so that it is difficult or impossible to reach it with the fingers. When this occurs, the upper section is pushed downward, as shown in Fig. 3.

If approximately half of the contents have been removed, the sections may be fully collapsed, but it will be apparent that they may be collapsed to any desired extent, to retain the level of the tobacco in the box at approximately the top thereof. The provision of the bosses insures easy assembling of the sections prior to packing, or during packing, and also facilitates the collapse of the box sections either fully or partially.

If the sections should stick, the bosses may be released from each other by springing of the sides of the upper section. The bosses, however, are of such shallow depth, that they are easily disengaged. The locking engagement between the sections is only at the bosses, the greater portion of the walls of the sections being merely slidably engaged. That is, the locking engagement between the sections is of a relatively negligible area, so that binding between the sections is reduced to a minimum.

The bosses are stamped in the sections, and the bosses of the two sections are complementary, that is, the bosses of the inner sec-

tions fit within the depressions formed by the stamping of the bosses in the outer section. When the sections are collapsed partially or completely, the bosses of the inner section, which as will be seen from inspection of Figures 2 and 3, are of less area and less height than those of the outer section to fit within the same, more relatively easily against the plane wall of the outer section, without any noticeable deformation of either section wall. That is, the outer bosses are external, so that they do not engage the other section, except as concerns the bosses of said other section.

By the terms "depressions" and "bosses" as herein employed, I do not wish to be understood as limiting myself to the substantially "spherical" protuberances shown in the drawings as obviously "stamped out" portions of other configurations which are complementary and which are arranged to interlock, may be employed without departing from the spirit of the invention.

It will be noticed referring to Fig. 1, that above a line connecting the upper edges of the bosses 8, the relative wide side walls of the lower section are bent inwardly at a slight angle to the body portions of the side walls. This is to insure a tight fit between the side walls of the sections. The bent-in portions at the top of the lower section which are bent at a very slight angle, are indicated at 9 in Fig. 1. It will be noticed that the bosses 8 are near the side edges of the relatively wide side walls, and near the commencement of the curvature of the end walls, so that there is a considerable degree of stiffness at this point and a substantial support.

The releasable lock; namely, the bosses, for holding the sections in fully extended position, is a feature of importance in boxes of this character. As was previously stated, the packages are inserted into the boxes by machinery, being pushed into the relatively stationary box by a plunger. If the box sections were freely slidable relative to each other, they would tend to collapse under the impetus of the plunger. In placing the label, considerable pressure is brought to bear against the ends of the box, since it must be held firmly, during the pressing of the label to place. There is also a tendency at this time to collapse the sections, if some interlocking mechanism is not provided to hold them extended. The interlocking bosses provides such a means.

In order to serve as a guide in the extension of the box, to show that it is fully extended, a boss 10 is provided at approximately the center of each of the long sides of the inner section, the said boss being so positioned that when the sections are fully extended, it will be just above the upper edge of the lower section, and just free from said edge. This boss also assists in pre-

venting accidental collapse of the sections during insertion of the package of tobacco. In extending the sections, ordinarily the snapping of the bosses 6 into the bosses 8 will indicate that the sections are fully extended, and the boss 10 is merely a precautionary arrangement, supplementing the sense of feeling by the sense of sight, in determining the full extension of the sections.

5 10 What is claimed as new is—

10 15 20 25 30 35 40 45 50 55 60 65 70 75 80 85 90 95 100 105 110 115 120 125 130 A packet tobacco box having oppositely arranged relatively wide substantially flat sides composed of two telescopic sections, one provided with a bottom permanently seamed thereto, and the other with a cover, the sections having complementary stamped out bosses arranged to interlock, with the bosses of the inner section fitting within the depressions formed by the stamping of the bosses on the outer section, when the sections are in extended position, and adapted to hold the sections temporarily extended, or partially extended by frictional engagement of the bosses of the inner section with the outer section wall, or to permit complete separation of the sections, the bosses being in the flat sides near the open ends of the sections.

2. A pocket tobacco box composed of two telescopic sections, one provided with a bottom and the other with a cover, the opposite side walls of the sections having complementary stamped out bosses arranged to interlock with the bosses of one section fitting within the complementary bosses of the other section when the sections are in extended position, and adapted to hold the sections temporarily extended, and to permit complete separation of the sections, said bosses being near the side edges of the side walls and at the beginning of the curvature of the end walls.

3. A pocket tobacco box composed of two telescopic sections, one provided with a bottom and the other with a cover, the opposite side walls of the sections having complementary stamped out bosses arranged to interlock with the bosses of one section fitting within the companion bosses of the other section when the sections are fully extended, and supplemental bosses on the said side walls of the inner section positioned to be exposed when the sections are fully extended, and serving to supplement the action of the first named bosses in holding the sections extended, said first named bosses being releasable to enable complete separation of the sections.

4. A pocket tobacco box, composed of telescopic sections, the opposite side walls of the sections having complementary stamped out rounded bosses adapted to interlock with the bosses of the inner section within the depressions formed by the stamping of the bosses on the outer section whereby to hold

the sections extended, said bosses being near the meeting ends of the sections, and on the flat sides of the sections near the beginning of the curvature of the rounded sides, and another boss on each flat side of the innermost section near the middle of each side wall near the end which meets the outer section, arranged to engage outside the edge of the lower section at the said end when the sections are extended.

5. A pocket tobacco box composed of two telescopic sections having plane relatively wide side walls, and relatively narrow end walls, the sections having complementary stamped out bosses arranged to interlock when the sections are fully extended, said bosses being on the plane sides near their junction with the relatively narrow sides for the purpose set forth.

Signed at New York city in the county of New York and State of New York this 2nd day of April A. D. 1929.
